UNITED STATES PATENT OFFICE.

LEWIS J. MORRISON, OF BOSTON, MASSACHUSETTS, ASSIGNOR TO UNITED SHOE MACHINERY CORPORATION, OF PATERSON, NEW JERSEY, A CORPORATION OF NEW JERSEY.

CHANNEL-FLAP-LAYING MACHINE.

1,415,946.

Specification of Letters Patent. Patented May 16, 1922.

Application filed April 12, 1920. Serial No. 373,079.

To all whom it may concern:

Be it known that I, LEWIS J. MORRISON, a citizen of the United States, residing at Boston, in the county of Suffolk and State of 5 Massachusetts, have invented certain new and useful Improvements in Channel-Flap-Laying Machines; and I do hereby declare the following to be a full, clear, and exact description of the invention, such as will 10 enable others skilled in the art to which it appertains to make and use the same.

This invention relates to machines for laying the channel flap on outsoles for boots and shoes and more particularly to improvements in the channel flap laying tools of 15 such machines.

In the manufacture of the cheaper grades of shoes it is customary to wipe down, or lay, the channel flap on the outsole by rubbing an ordinary steel file diagonally across 20 the margin of the sole, the teeth of the file first having been dulled to prevent them from tearing the stock. The surface thus produced on the file has the required tractive quality for carrying the flap over the channel although with some undesirable roughening of the stock. For the better 25 grades of shoes it has been customary to use the Goodyear channel flap laying machine disclosed in Letters Patent of the 30 United States No. 981,190, granted January 10, 1911 to John B. Hadaway. The rotary tool of this machine comprises a series of flap engaging blades which impart a succession of alternate longitudinal and transverse glancing blows to the flap and thus 35 turn it back on the channel. This tool preferably is made of metal and hence the surfaces of its flap engaging blades are smooth 40 and wholly without tractive effect on the flap except what is due to friction. The process of manufacturing shoes is such that after the outsole channel has been cut, the later operations on the shoe cause a distinct 45 broadening of the channel without affecting the width of the flap. In McKay work this occurs while moulding the sole on the last and in welt work at both the leveling and outer sole stitching operations. Under these 50 conditions when the flap is laid by the machine referred to, it does not fill the broadened channel thus spoiling the appearance of the bottom of the shoe. It has been discovered that this undesirable condition is 55 due to the nature of the material from

which the tool is made which necessarily provides smooth, non-tractive flap engaging surfaces having no tendency or power to stretch the flap sufficiently to completely fill the broadened channel. It will not do to 60 roughen the ends of the flap engaging blades because the blow which the tool is designed to give would then be so harsh as to split the flap as it is being turned back on the channel, especially when the temper of the 65 stock is imperfect. This would cause a cripple, but those skilled in the art will recognize that if the blow can be softened the tractive effect can then be added without the danger of producing 70 cripes.

The object of the present invention is to combine with the rigid blade of a channel flap laying tool of the Goodyear type a yielding tractive element, preferably with a tractive surface, which cooperates with the 75 blades of the tool in a manner to dampen or soften the glancing blows to which the channel flap is subjected.

To the full accomplishment of this object it is proposed to interpose between the tool 80 and work an element having a surface which is sufficiently rough to grip the channel flap to the required extent and to draw and stretch the flap as it is laid, but which also is flexible and continuous across and between all of the blow delivering blades of 85 the tool, so that while at all times supported by these blades the result of its working back and forth and its texture is to produce a cushioning effect to the blow delivered to 90 the channel flap. Any yielding material conformable to the shape of the tool may be employed as the cushioning element, but it is preferred to employ heavy duck or canvas since such woven fabric when stretched 95 over the blow-delivering blades of the tool offers the added advantage of a surface with sufficient tractive power to stretch the flap. The cushioning element is so shaped as to provide a continuous surface over the entire face of the flap laying tool, it being immaterial how this is accomplished if so arranged as to be in contact with the stock engaging portion of the tool thereby bridging the spaces between the blades. A flap 105 laying tool of the Goodyear type having a continuous element with a tractive surface combined therewith will operate upon the channel flap in a manner to stretch it without leaving any harmful mark thereon. 110

Any yielding element covering the blow delivering blades of the Goodyear type tool, because of its flexible character and arrangement relative to the tool, will reduce the harshness of the blows delivered and act successfully to lay without splitting, channel flaps which are somewhat brittle because not in proper temper.

It will be obvious, therefore, to those skilled in the art, that a flap laying tool having the combination of elements described will add quality, accuracy and perfection to shoemaking, since its use will overcome all irregularity and lack of uniformity now resulting from the use of the flap laying tools at present available.

The invention comprises the features and combinations of parts hereinafter described in detail and then defined in its true scope in the appended claims.

In the accompanying drawings illustrating the invention Figure 1 shows a rear view of the flap laying tool of said Hadaway Patent No. 981,190 having combined therewith one form of the blow dampening and flap stretching element; Fig. 2 is a longitudinal section on the line 2—2 of Fig. 1; Fig. 3 is a front elevation of the flap laying tool of the Hadaway patent having combined therewith another form of the blow dampening and flap stretching element; and Fig. 4 is a longitudinal section on the line 4—4 of Fig. 3.

The invention, in both forms illustrated in the drawings, comprises in its entirety two main elements, namely, a blow delivering element such as the tool of said Hadaway patent with its rigid, metallic flap laying blades, and a blow dampening and flap stretching element which affords direct contact with the stock being operated upon.

Referring first to all four figures of the drawings the rotary wheel 6 which carries the blow delivering blades is mounted for a longitudinal yielding movement, through a spring 8, on a driving shaft 10 having fast and loose pulleys (not shown) at the rear end, all as described in said Hadaway patent. The blow delivering blades project from one face of a metallic annulus 12 which is secured by set screws 14 to the outer face of the wheel 6. These blades are in the form of a zig-zag rib 16 and two rows of alternating radial blades 18 and 20, there being spaces between the three series of blades as shown best by Figs. 2 and 4. The blade construction illustrated is that of said Hadaway patent, but those skilled in the art will recognize that the utility of the present improvement is not limited to that particular blade construction alone as any blade construction having like characteristics or a like means of delivering a succession of blows may be combined with the blow dampening element. Referring now to

the form of the invention shown in Figs. 1 and 2, the blow dampening element therein depicted comprises a member 22 of yielding material carried by the wheel 6 in a manner to cover the operating faces of the rigid flap laying blades whereby the blows will be delivered through said element and the harshness of the blows thereby softened. To overcome the disadvantage, hereinbefore referred to, of the smooth, non-tractive surfaces offered by the metallic blades, it is preferred that the member 22 be formed of material the surface of which has tractive qualities, such as heavy canvas. In Figs. 1 and 2 the member 22 is circular and preferably two ply to increase resiliency and wearing quality. Grommets 24 are set around its margin, through which a draw string 26 is run. The member 22 is drawn, with reasonable tightness, across the operating faces of the blades, bridging the spaces between the three series thereof, and is held in place by tying together the ends of the draw string at the back of the wheel 6, as shown in Fig. 1. The yielding action of the member 22 while continuously in engagement with the channel flap, and the smoothing effect thereof on the action of the blades, will be understood by those skilled in the art as particularly advantageous when operating on stock that is dry or brittle because not in proper temper at the time the flap turning operation is performed, all as hereinbefore explained.

In Figs. 3 and 4 a modified form of the blow dampening element is illustrated. A slight disadvantage inherent in the form shown in Figs. 1 and 2 is the inability of the operator to manipulate the shoe to the best advantage because of the continuity of the canvas across the hollow center of the wheel 6. Accordingly in the modified form a two ply canvas member 28 of cylindrical form is employed, the two layers of which are secured together by two parallel lines of stitching 30 and 32 at each margin forming pockets for draw strings 34 and 36. The diameter of the member 28 is substantially the diameter of the annulus 12 and it is positioned on the annulus as shown best in Fig. 2, the tying of the draw strings holding it firmly in place. The effect on the channel flap is the same in the use of either form of the blow dampening element, that is, the succession of glancing blows from the blades are less harsh and the tool is enabled to stretch the flap to completely fill the channel, thus perfecting this particular operation on the shoe.

The nature and scope of the invention having been indicated and its preferred embodiment having been specifically described, what is claimed as new, is:—

1. A channel flap laying machine having, in combination, a flap laying tool comprising

a series of unyielding elements for delivering a succession of blows to the channel flap, and yielding means in engagement with the operative faces of such elements and bridging the spaces therebetween, whereby the blows are delivered through the yielding means and are damped or softened.

2. A channel flap laying machine having, in combination, a flap laying tool comprising a series of metallic elements for delivering a succession of blows to the channel flap, and a piece of flexible material overlying the entire series of such elements through which the blows are delivered and their harshness reduced.

3. A channel flap laying machine having, in combination, a flap laying tool comprising a series of rigid elements having smooth, non-tractive, operative faces for delivering a succession of blows to the channel flap, and a continuous element carried by said rigid elements comprising a member constructed to engage the channel flap with a tractive effect.

4. A channel flap laying machine having, in combination, a flap laying tool comprising a series of rigid elements having smooth, non-tractive, operative faces for delivering a succession of blows to the channel flap, and a piece of heavy canvas laid in contact with the smooth faces of said rigid elements the texture of which provides a tractive surface for engaging the channel flap.

5. A channel flap laying machine of the type in which the tool comprises a rotary

annulus having a series of rigid, metallic flap laying blades projecting from one flat face thereof having, in combination with said blades, means movable therewith for reducing the harshness of the blows delivered by said blades, said means comprising a relatively thick, non-metallic member having an uninterrupted surface extending across and covering the operative faces of the entire series of blades.

6. A channel flap laying machine of the type in which the tool comprises a rotary annulus having a series of rigid, metallic flap laying blades projecting from one flat face thereof having, in combination with said blades, a heavy canvas covering so mounted on the annulus that the blades are constrained to act therethrough, said canvas providing a yielding element continuously engaging the channel flap by virtue of which the successive blows delivered by the blades are partly merged into each other and their harshness reduced.

7. A channel flap laying machine of the type in which the tool comprises a rotary annulus having a series of rigid, metallic flap laying blades projecting from one flat face thereof for delivering a succession of blows to the channel flap, having means continuously in engagement with the operative faces of the entire series of blades for cushioning the force of said blows on the channel flap.

LEWIS J. MORRISON.
